Primary Examiner — Michael C Stout*Assistant Examiner* — Katelin G Kloberg(74) *Attorney, Agent, or Firm* — Cook Alex Ltd.(57) **CLAIM**

The ornamental design for a bed, as shown and described.

DESCRIPTION

FIG. 1 is a perspective view of a bed, showing a first embodiment of our new design;

FIG. 2 is a front elevational view of the bed;

FIG. 3 is a rear elevational view of the bed;

FIG. 4 is a left side elevational view of the bed;

FIG. 5 is a right side elevational view of the bed;

FIG. 6 is a top plan view of the bed;

FIG. 7 is a bottom plan view of the bed;

FIG. 8 is a perspective view of the bed with the right side shelf extended;

FIG. 9 is an exploded perspective view of the bed, showing the right side shelf extended and the storage space lid removed; and,

FIG. 10 is a perspective view of a second embodiment of the bed wherein the extendable shelf is on the left side of the bed.

The broken line portions of the drawings are included to show portions of the article that form no part of the claimed design and represent environmental structure only.

1 Claim, 10 Drawing Sheets(56)
